BY

UNITED STATES PATENT OFFICE.

THOMAS McCREA FULTON, OF HAWTHORN, VICTORIA, AUSTRALIA.

CASEMENT-WINDOW FITTING.

Application filed December 13, 1922. Serial No. 606,712.

To all whom it may concern:

Be it known that I, THOMAS McCREA FULTON, a British subject, residing at No. 21 Morang Road, Hawthorn, in the State of Victoria, Commonwealth of Australia, have invented new and useful Improvements in Casement-Window Fittings, of which the following is a specification.

This invention relates to improvements

- 10 in casement window fittings which improvements embody novel means for readily and effectively locking and unlocking the window lever or guide rod after the position of the window has been adjusted.
- 15 The construction of the window fittings is also such as to permit of the employment of a fly proof screen blind or the like on the inside of the window and which screen is suitably supported on a wooden batten secured to the lower sash framing and resting on the window sill.

This window batten or screen support is suitably recessed and holed to receive the window lever or guide rod and a slidable plate carrying same and which permits of the movement of the lever without interfering with the screen, which feature is not possible in the present construction of casement window fittings.

- 20
  - 25
  - 30
  - 35
  - 40
  - 45
- The window lever or guide rod employed herein is pivotally jointed to a stock and comprises two concentrically disposed tubular members, both of which have a number of equidistant holes, in their adjacent sides. The inner tube is adapted to be revolved within the outer one and is provided with a number of locking slots which lead from the holes therein and adapted to be engaged by an inwardly projecting locking tongue which latter forms part of a cover plate secured to the inner face of the screen supporting batten.

In order to securely lock the lever when the position of the window has been adjusted the lever is drawn towards the locking tongue and when the holes in both tubes are in apposition the inner tube is turned downwards and towards the tongue when the slots in the inner tube are engaged by the said

tongue and securely held or jambied therein. By turning the locking tube in the opposite direction the slots therein are freed or disengaged from the tongue permitting the window to be again adjusted as is desired.

The invention will now be described having reference to the accompanying drawings, in which—

Fig. 1 is a plan, and

Fig. 2 is a vertical sectional elevation of a casement window and fittings assembled together according to this invention.

Fig. 3 is an elevation of a cover plate which is slotted to receive the window lever or guide rod.

Fig. 4 is a part sectional plan of Fig. 3.

Fig. 5 is an enlarged fragmentary part of Fig. 3 showing the window lever or guide rod locked by a locking tongue.

Fig. 6 is a part sectional elevation of the window lever or guide rod, and

Fig. 7 is a detail of Fig. 6.

In constructing the improved window fittings I employ a transverse wooden batten A of a suitable height and thickness which is supported on the window sill F and is suitably screwed or secured to the sash frame G. The inner surface of the said batten A is recessed as at A¹ and provided with a central opening A² for the reception of a slidable plate and lever respectively.

The front of the recess A¹ is closed by a cover plate B which is suitably screwed to the batten A the recess being adapted to house a slidable plate C, the latter being centrally holed at C¹ to receive the window lever or guide rod. The said lever or guide rod comprises two concentrically disposed tubes D and D¹, and an arm D² which is flexibly connected or jointed at d² to the outer tube D. A number of equidistant holes d is formed in the side of the tube D and which are in apposition and adapted to register with a corresponding number of holes d¹ formed in the inner tube D¹, the said holes d¹ having extended slots or grooves d² formed in the circumference of the tube D¹.

The cover plate B is provided with a slot

5 *b*, one of the side edges of which is formed with an inwardly projecting locking tongue or member *b*¹ which is adapted to be engaged by a set of holes *d*—*d*¹ after the position of the casement window has been suitably adjusted, the inner tube *D*¹ being turned to bring one of the narrow slots or extensions *d*² into engagement with the tongue *b*¹, the said groove gripping or 10 surely holding the latter which is formed with a slight outward curve, thus securely holding and locking the guide rod or lever. The inner tube *D*¹ is provided with a knurled head or knob *d*⁴ in order that it may be 15 conveniently turned and the window locked or unlocked, as the case may be.

10 The head *d*⁴ is also provided with a solid neck *d*⁵ which is secured to the inner tube while the outer tube *D* is provided with a 20 semi-circular slot *d*⁶ for engagement with a set screw *d*⁷ which slot and screw permit and limit the oscillatory or turning movement of the inner tube *D*¹.

When the window is being opened or 25 closed and the window lever or guide rod is being thrust forward or backward the slideable plate *C* is reciprocated laterally in the recess *A*¹ and acts as a guide for the said window lever or guide rod. When the desired adjustment of the window has been 30 made it is only necessary to draw the lever *D*—*D*¹ towards the locking tongue and engage the latter with the holes *d* and *d*¹ respectively, thus securely locking the window.

35 The improved construction of window fittings herein enable a fly-proof screen to be used in conjunction with a casement window the screen *H* being positioned on the inside of the window and resting on top of 40 the batten *A* and which arrangement enables a screen to be effectively used with a casement window without interfering with the movement of the guide rod or lever or

of the window itself as would occur with the fittings at present in use.

Having now described my invention what I claim as new and desire to secure by Letters Patent is:—

1. Improvements in casement window fittings comprising, in combination, a vertically mounted screen support having a recess and an opening therein and secured to the sash framing, a slotted cover plate secured to said screen support and positioned over the recess in said support, a locking tongue formed with said plate, a vertically mounted slideable plate formed with a hole therethrough housed in the recess of said screen support, a window lever pivotally connected to a stock and carried by said slideable plate, and means for locking said lever to and disengaging the same from said locking tongue.

2. In casement window fittings, in combination, a screen support having an inner recess therein, a cover plate positioned over the recess of said screen support, locking means on said cover plate, a slideable plate formed with a hole therethrough housed and working in the recess of said support, a window lever working in the slideable plate and comprising concentrically arranged tubular members, a window stock pivotally connected to the said tubular members, means for engaging said tubular members with said locking means on said cover plate and for disengaging said members from the said locking means.

In testimony whereof I have signed my name to this specification in the presence of 80 two subscribing witnesses.

THOMAS McCREA FULTON.
